UNITED STATES PATENT OFFICE.

JAMES BLICK, OF CAMDEN TOWN, ENGLAND.

IMPROVEMENT IN MACHINES FOR UNTWISTING AND CARDING ROPE.

Specification forming part of Letters Patent No. 126,868, dated May 21, 1872.

To all whom it may concern:

Be it known that I, JAMES BLICK, of Camden Town, county of Middlesex, England, have invented "a new or Improved Machine for Untwisting and Carding Rope;" and do hereby declare that the following description, taken in connection with the accompanying sheets of drawing, hereinafter referred to, forms a full and exact specification of the same, wherein I have set forth the nature and principles of my said improvement, by which my invention may be distinguished from others of a similar class, together with such parts as I claim and desire to secure by Letters Patent—that is to say:

My invention has for its object the construction of a new or improved machine for untwisting and combing or carding hair or other similar fibrous substances that have been previously twisted into the form of rope.

The construction of and mode of operating with the said machine will be readily understood on reference to the accompanying sheets of drawing, on which—

Figure 1 shows a side elevation of the machine. Fig. 2 shows a plan of the same. Fig. 3 shows a front end elevation. Fig. 4 shows a longitudinal section, and Figs. 5 and 6 show detached details to an enlarged scale.

Similar letters of reference indicate similar parts throughout the figures.

The framing A of the machine carries at the front end a revolving frame, B, containing the reel C, upon which is wound the hair or other fibrous substance D in the form of a rope to be operated upon. The frame B is rotated on the pivot B¹ at the bottom by means of the belt E' from the pulley E, driven by the pinion F², receiving motion from the spur-wheel F. The reel C turns freely in its bearings in the frame A, and at the same time revolves with it. The rope of hair D is led from the reel between a pair of nipping-rollers, B², fixed to the top of the framing, and consequently revolving with it. The rollers B² may be drawn together by means of springs B³, so as to nip the rope, and yet be capable of yielding to any inequalities in the thickness thereof. From between these nipping-rollers the hair passes over a table, G', to between a pair of feed-rollers, H, which draw the hair from the reel and feed it into the other part of the

machine. As the hair-rope is thus drawn off the reel into the machine it is at the same time untwisted in the space between the nipping-rollers B² and the table G' by the revolving motion of the nipping-rollers. As the hair passes from the nipping-rollers over the table G' to the feed-rollers H, it is opened out somewhat by hand by an attendant, and in this condition it passes from the feed-rollers onto the spreading-cylinder I. This cylinder has a series of grooves, I¹, in each of which are two sliding plates, I², with teeth I³, which, as the cylinder revolves in the direction of the arrow, are made to project out of the groove, so as to enter the hair as it passes from the feed-rollers H onto the cylinder. These teeth are situated close together as they enter the hair at the feed-rollers H, and as the cylinder revolves they are made to separate from each other, thereby spreading out the hair upon the cylinder, as shown at Fig. 2, as it is carried by the latter toward the second pair of feed-rollers K. Arrived at these latter feed-rollers, the teeth I³ are suddenly drawn inward into the cylinder, as shown at Fig. 4, so as to release the hair and prevent its being dragged beyond the feed-rollers; and as they pass on toward the feed-rollers H again, they are gradually moved radially outward, and are at the same time drawn close together. For effecting these motions of the teeth I³, devices are employed, which are shown more clearly in the enlarged end view and longitudinal section of the cylinder I at Figs. 5 and 6. The plates I² are connected to each other by means of a plate, I⁶, this plate having studs sliding in slots in the plates I², while these have other studs sliding in slots in the plate I⁶, as shown clearly in Fig. 6. At each end of the cylinder I is a cam, L, fixed to the framing A by brackets L', which cams have, first, a cam-surface, l, formed on their peripheries, upon which the sliding plates I² bear, and which effect the outward radial motion of the plates I² and teeth I³, the inward motion thereof being effected by springs I⁴ connected to the plates I² and to the spindle I⁷ of the cylinder I. Secondly, the cams have other cam-surfaces, l', formed on their edges, against which the sliding plates I² bear by means of small rollers I⁵, so that they are gradually drawn out away from each other by these cam-surfaces as they pass from

the rollers H to the rollers K, while as the plates pass back to the rollers H they are drawn inward toward each other by means of springs I⁶ attached thereto and to the plate I⁶. The feed-rollers K deliver the hair in an opened-out condition onto an endless traveling-card surface, M, stretched over three rollers, M', which cards or combs the hair, and at the same time brings it under the revolving cylinder N. This cylinder is somewhat similar in construction to the cylinder I, having a series of grooves, N¹, in which are plates N² having rows of teeth N³, which, as the cylinder revolves in the direction of the arrow, are gradually pushed outward through holes in the plates N⁴, covering the grooves as they approach the card-surface, and are then suddenly drawn in again after passing beyond the card-surface. By this arrangement, as the cylinder N revolves at a greater speed than the card-surface, the teeth N³, in entering the hair on the latter, comb it and at the same time draw it off of the card-surface and deliver it onto the chute O, whence the hair falls in a perfectly-loose condition into the basket or other receptacle P. For effecting the before-described motion of the plates N² and teeth N³, two fixed cams, Q Q, are placed one on each side of the cylinder, having a configuration, as shown at Fig. 1, and upon these cams the ends of the plates N² bear by means of small rollers N⁵, so that they are forced outward thereby as they approach the card-surface M, and they are then drawn suddenly in again after passing the points 9 of the cams by means of springs N⁶ attached to the plates and to the spindle of the cylinder N, as shown at Fig. 4. Any hair remaining attached to the card-surface M after passing under the teeth N³ is removed therefrom by a series of fixed teeth, O', projecting from the edge of the chute O between the wires of the card-surface, as indicated at Fig. 4.

Rotary motion is imparted to the various before-described parts of the machine by means of the spur-wheel R, driven either by hand or by power. This wheel is in gear with the wheel F, which imparts motion directly to the gearing S for the cylinder N. On the other end of the shaft F¹ of the wheel F is a pinion, F², in gear with a wheel, T, which drives the pinion U, actuating the one roller M' of the card-belt M, and also the wheel V on the shaft of the cylinder I. This wheel is in gear with two pinions, W X, which respectively drive other pinions on the shafts of the lower feed-rollers H and K.

As the hair-ropes vary somewhat in the degree to which they have been twisted in the first instance, it is necessary to be able to regulate the speed of rotation of the frame B according to the amount of twist in the particular rope to be operated upon. This is effected by means of a brake-strap, a, which may be applied with greater or less force to the grooved disk B⁴ at the bottom of the frame by means

of a treadle, a', so as to retard the rotation of the frame B, more or less, which retardation is permitted in causing the driving-belt E' to slip in its groove on the frame.

In the above-described machine, instead of effecting the partial opening out of the hair by hand as it passes from the frame B to the feed-rollers H, this may be effected by means of the device shown at Figs. 7, 8, and 9. Fig. 7 is a plan, and Fig. 8 is an elevation of parts, which for this purpose may be substituted for the roller G and feed-table G', described above. g is a feeding-table having a flat vertical face, and r is the shaft of the wheel R represented in the other figures. On this shaft there are two cams, a a, shown in elevation in Fig. 9, and there are two grooved cams, b b. Two slides, c c, are mounted on the framing, and each of these slides has jointed to it a vibrating arm, d, furnished with projecting points or teeth e. On these vibrating arms d are blocks f f bearing against the cams a a, toward which the arms are pressed by springs h h. The slides c c have also pins projecting into the grooves of the cams b b. As the shaft r revolves the action of the cams and springs causes the points e e to approach each other; then to close in toward the vertical face of the table g, and thus to insert themselves among the fibers of untwisted rope passing over that face. The points thus inserted among the fibers are then caused to withdraw from each other, and so to spread the fibers laterally. Having completed their outward stroke, the points are then caused to disengage themselves from the fibers by moving back from the vertical face of the table g, and when so disengaged to return toward each other and repeat the operation at each successive revolution of the shaft r.

Having thus described the nature of my invention, and in what manner the same is to be performed, I wish it to be understood that I do not limit myself to the precise details of the various parts of the machine, as hereinbefore described and shown on the accompanying drawing, as it will be evident that these may be variously modified without departing from the essential features of my invention. Thus other mechanical equivalents may be substituted for the cams and other devices for producing the before-described movements of the teeth of the cylinders I and N; also, in place of the traveling-card surface M, might be employed a rotating cylinder having card-surfaces; but

What I claim is—

1. The combination, in a machine for untwisting and combing or carding hair and other similar fibrous substances, of a rotating frame, B, with reel C and nipping-rollers B² for untwisting the ropes of hair, a spreading-cylinder, I, with advancing and receding teeth I³ for spreading out the untwisted hair, a traveling-card surface, M, for carding or combing the hair, and a cylinder, N, with advancing

and receding teeth N^3 for removing the hair from the card-surface, the whole operating substantially in the manner hereinbefore set forth.

2. The combination of the feed-rollers H, spreading-cylinder I, feed-rollers K, traveling card surface M, and combing-cylinder N for opening out, combing, and separating hair or other fibrous materials, substantially as set forth.

3. In a hair-untwisting machine, a cage, B, and reel C, for unwinding and untwisting the rope, in combination with a series of teeth, I^3 , mounted in a revolving cylinder, I, and operative toward and from each other, and thereby opening out or spreading the fibers or strands, substantially as described.

4. The device shown at Figs. 7 to 9, consisting of the slides c with vibrating arms d, having teeth e operated by cams a and b, and springs h for partially opening out the hair as it passes from the cage B to the feed-rollers H, substantially as set forth.

In testimony whereof I have signed my name to this specification in the presence of two subscribing witnesses this 7th day of November, 1871.

JAMES BLICK.

Witnesses:

CHAS. D. ABEL,
JNO. P. M. MILLARD.

1. The combination of a series of feed-rollers H, a spreading-cylinder I, feed-rollers K, traveling card surface M, and combing-cylinder N for opening out, combing, and separating hair or other fibrous materials, substantially as set forth.

2. The combination of the feed-rollers H, spreading-cylinder I, feed-rollers K, traveling card surface M, and combing-cylinder N for opening out, combing, and separating hair or other fibrous materials, substantially as set forth.

3. In a hair-untwisting machine, a cage, B, and reel C, for unwinding and untwisting the rope, in combination with a series of teeth, I^3 , mounted in a revolving cylinder, I, and operative toward and from each other, and thereby opening out or spreading the fibers or strands, substantially as described.

4. The device shown at Figs. 7 to 9, consisting of the slides c with vibrating arms d, having teeth e operated by cams a and b, and springs h for partially opening out the hair as it passes from the cage B to the feed-rollers H, substantially as set forth.

In testimony whereof I have signed my name to this specification in the presence of two subscribing witnesses this 7th day of November, 1871.

JAMES BLICK.
